Primary Examiner — Mary Ann Calabrese*Assistant Examiner* — Natalya M Rapundalo(74) Attorney, Agent, or Firm — Miller & Martin PLLC(57) CLAIM

The ornamental design for a gravity fed smoker, as shown and described.

DESCRIPTION

FIG. 1 is a right side perspective view of the gravity fed smoker of the present invention;

FIG. 2 is a front elevation view of the gravity fed smoker;

FIG. 3 is a back elevation view of the gravity fed smoker;

FIG. 4 is a right side elevation view of the gravity fed smoker;

FIG. 5 is a left side elevation view of the gravity fed smoker; and,

FIG. 6 is a top view of the gravity fed smoker.

The broken lines shown form no part of the claimed design.

1 Claim, 6 Drawing Sheets(56)
